UNITED STATES PATENT OFFICE.

FRANK C. WEBB, OF PORTLAND, OREGON.

SWIMMING GLOVE.

Application filed September 11, 1925. Serial No. 55,715.

This invention relates to swimming gloves and has for its primary object, the provision of a glove wherein means is provided for normally holding the fingers distended 5 to offer a maximum area, but which may be easily and quickly collapsed by movement of the wrist of the swimmer to offer minimum resistance in the return stroke.

A further object is to provide a swimming 10 glove of this general character which shall be simple in construction, inexpensive to manufacture, and which may be easily and quickly applied or removed from the hands.

With these and other objects in view, the 15 invention may be stated to consist in the provision of a glove having webs formed between the fingers thereof, and a reinforced wrist portion to secure the same to the hand, there being an adjustable cord or similar element extending from one side of the aforementioned wrist portion to the little finger and thence around the tips of the fingers and from the thumb to the opposite side of the wrist portion.

25 In the drawing accompanying and forming a part of this application,

Fig. 1 is a top plan view of a glove constructed in accordance with my invention and showing the same applied to the hand; 30 and

Fig. 2 is a transverse sectional view taken on the line 2—2 of Fig. 1.

In carrying out my invention, I provide a glove 1 having fingers 2 and a wrist portion 3. Intermediate the fingers 2 there are formed webs 4, and extending between the little finger and wrist portion and thumb and wrist portion are webs 5 and 6 respectively.

40 I preferably form the wrist portion 3 with a longitudinal slit 7 to enable the glove to be easily fitted to, or removed from the hand, and in order to securely retain the glove in position, I provide straps 8 which are arranged in spaced relation and disposed about the wrist portion. These straps are normally held in spaced relation by oppositely disposed rigid side members 9 which are riveted thereto and also through the 45 wrist portion 3, as indicated at 10, or fastened in any other approved manner.

I am aware that it has been proposed heretofore to provide a glove having webs between the fingers, but with this arrangement, the pressure of water on such webs is 55 so great that it is impossible for the swim-

mer to hold the fingers distended and thus secure maximum area of the glove. Even with the fingers partially distended, this form of swimming glove causes considerable strain on the hand to hold the fingers separated. In order to overcome this serious objection, I attach a cord 12 or other suitable element to one of the aforementioned wrist straps 8 and extend such cord 60 to the tip of the little finger, thence about the tips of the other fingers and thumb, and adjustably fasten the end thereof to the opposite side of strap 8. The cord 12 is preferably enclosed in a seam 13 formed from 65 the webs 4, 5 and 6 and either one or both ends of the cord may be adjustably fastened to the strap 8 to vary the tension thereof.

In use, a glove will be applied to each 70 hand and straps 8 tightened about the wrists to hold the gloves in position. The cord 12 of each glove is then adjusted to the proper tension with the fingers fully distended, and on each stroke, this cord will serve to retain 75 the fingers separated and thus relieve the strain on the fingers of the swimmer. The rigid members 9 prevent the straps 8 from slipping toward each other and at the same time permit movement of the wrist. At the 80 finish of the stroke, the hand may be moved at the wrist to shorten the normal distance from the tips of the fingers to the wrist, whereupon the hand may be closed and the 85 return stroke accomplished with relatively 90 small area of the glove and hand exposed. It is thus apparent that I have provided a glove which will greatly assist in the propulsion of the swimmer and which will relieve him of all strains incident to the increased area of the glove over that of the 95 hand.

I claim:

1. A swimming appliance of the character set forth comprising a glove having a wrist portion and webs between the fingers and thumb thereof, an element connecting said fingers, thumb and wrist portion and tending normally to hold said fingers and thumb distended, and means for varying the tension 100 on said element.

2. A swimming appliance of the character set forth comprising a glove having a wrist portion and webs between the fingers and thumb thereof, a plurality of straps disposed about said wrist portion, means for retaining 110 said straps in spaced relation, an element

connected to one of said straps and extending about the tips of said fingers and thumb and connected at the opposite end to said strap, and means for varying the tension on said element to normally hold said fingers and thumb distended.

3. A swimming appliance of the character set forth comprising a glove having a wrist portion and webs extending between the fingers and thumb thereof, a pair of straps disposed about said wrist portion and fastened thereto, rigid members interconnecting said

straps and retaining the same in spaced relation, a cord connected to one of said straps and extending about the tips of said fingers and thumb and connected at the opposite end to the opposite side of said strap, means for varying the tension on said cord, and webs extending between said cord and little finger and wrist portion and between said thumb and wrist portion.

In testimony whereof I affix my signature.

FRANK C. WEBB.
